UNITED STATES PATENT OFFICE.

WILLIAM G. KENDALL, OF NEWARK, NEW JERSEY.

COMPACT EJECTOR FOR VANITY CASES.

Application filed January 26, 1927. Serial No. 163,731.

This invention relates to vanity cases and particularly to an improved compact ejector therefor.

The object of the invention is to provide 5 an improved ejector which may be pulled or pushed for loosening a compact in a vanity case whereby the compact may be readily removed.

Another object of the invention is to provide 10 a compact ejector which will act in the double capacity of means for holding a compact in place and means for ejecting or removing the compact.

In the accompanying drawing—
15 Figure 1 is a plan view of a vanity case shown open, the same being illustrated as fitted with an ejector embodying the invention.

Figure 2 is a sectional view through Fig-
20 ure 1 on line 2—2.

Figure 3 is an enlarged fragmentary sec-
25 tional view of the right hand portion of Figure 2, illustrating more in detail how the compact is held in place.

Figure 4 is an enlarged sectional view of
25 the left hand portion of Figure 1, illustrating a second holding means for the compact.

Figure 5 is a perspective view of the hold-
30 ing ring shown in Figure 2.

Figure 6 is a perspective view of the ejector
35 shown in Figure 3.

Figure 7 is a view similar to Figure 3 but showing a slightly modified construction.

Referring to the accompanying drawing
35 by numerals 1 indicates the body of a vanity case, said body being provided with a lid or cover 2 hingedly connected at 3 to the body. Arranged in the body 1 is a holding ring 4 which may be held in position in any 40 desired manner, as for instance, by being pinched beneath the clamping ring 5 arranged in the groove 6. The ring 4 is pro-
45 vided with a groove 7 which is at the dia-
metrically opposite side to the ejector mem-
ber 8. From Figure 4 it will be noted that
50 the annular edge or bead 9 fits loosely into
groove 7 so that when the ejector member 8
is pulled upwardly from the position shown
in Figures 2 and 3, the inturned flange 10
55 will crowd the compact plate 11 over so that
part of the bead 9 will be forced further
into the groove 7 and thereby permit the
proper movement of the plate 11 upwardly.
This crowding is very slight and under some
55 circumstances, might be dispensed with,

though it is desirable particularly where the groove 12 is utilized. When the ejector structure 8 is forced downwardly to the position shown in Figures 2 and 3, the plate 11 will be crowded over slightly or sufficient-
60 ly for the bead 9 to snap into the groove 12, where it is retained until the ejector structure 8 is pulled upwardly. This structure is somewhat resilient so that a slight tension is provided at all times. It will be noted
65 that the surface 13 of the ejector structure 8 bears against the inner surface of ring 4 and also the leg 14 slides in slot 15 whereby it will assist in holding the structure in proper operative position. A lug or projec-
70 tion 16 (Figure 6) is provided on leg 14 so as to prevent the accidental removal of the device through the slot 15.

In Figure 7, a slightly modified form of the invention is shown wherein the ejector structure 8 is provided with a comparatively sharpened end 17 instead of a flange 10. In this form of the invention, the ring 4 is provided with a bur or raised portion 18 and the center of this bur or raised portion 80 is so positioned as to be slightly above the largest periphery of the bead 9 whereby the bur 18 acts with the material forming groove 7 to hold the compact plate 11 in the position shown in Figure 2. When it is desired
85 to eject or remove plate 11, the member 8' is merely pushed downwardly as shown in Figure 7, the downward movement being preferably carried out until the upper part of ring 4 prevents further movement. As 90 this ejecting movement takes place, the wedge-shaped end 17 will crowd in between the bead 9 and the bur 18 and will crowd the opposite edge of bead 9 further into the groove 7. This action by reason of the fact
95 that the plate 11 is resting on the bottom of body 1 will cause the plate 11 to become loose and, consequently, may be readily removed by inverting the body 1. The ring 4 and particularly the downwardly extending 100 portion carrying the groove 7 is resilient so that as soon as the ejector 8' has been forced downwardly, this resilient action will have to cause the plate 11 to move slightly upwardly adjacent the ejecting structure 8'. By forcing the ejector structure 8' downwardly, the holding means at this point is eliminated as far as the plate 11 is concerned and, consequently, even if the parts 105 remain comparatively tight, the plate 11 may 110

be readily removed by inverting the body 1 and striking the same against the hand or some object with a slight blow.

What I claim is:

- 5 1. In a vanity case provided with a compact plate, of means for holding said plate in position, said means including a holding ring, and an ejecting structure carried by said ring capable of movement in line parallel to the axis of the compact plate, said ejecting structure being formed with means when moved parallel to said axis to loosen and disconnect the plate from said ring.
- 10 2. In a vanity case provided with a compact plate, of an ejector operatively associated with the case and positioned to reciprocate therein, said ejector having a flat body formed at one point with a depressed portion on one face and a flange at one end whereby when the ejector is moved in one direction the grooved portion acts to hold the compact plate in the case and when moved in the opposite direction the flange acts to eject said plate.
- 15 25 3. The combination with a vanity case having a compact plate, of a holding ring arranged in said compact and operatively associated with said compact plate, a sliding ejecting structure carried by said ring and acting to eject said plate when slid in a direction parallel to the axis of said plate.
- 20 4. The combination with a vanity case provided with a compact plate, of a holding ring mounted in said vanity case and acting to normally hold the compact plate therein, and a substantially U-shaped ejector slidably mounted on said ring with one leg of the U-shaped structure operatively associated with the ring and plate for ejecting the plate when the U-shaped member is moved in one direction said ejector having on one leg a recess acting to retain said plate in said case,

and a flange for ejecting the plate when the ejector is moved in a direction substantially at right angles to the plane of said plate. 45

5. In a vanity case provided with a compact plate, of an ejector formed substantially U-shaped in cross section and having a flange at one end of one leg of the U-shaped structure, and a looped portion spaced from said flange adapted to normally receive part of said compact plate for holding the same in a vanity case, said flange functioning to eject said plate when said U-shaped structure is pulled in a given direction. 55

6. In a vanity case provided with a compact plate, of a holding ring normally mounted in the vanity case and provided at one point with a depression or groove for receiving part of one edge of said plate, and an ejecting structure on the diametrically opposite side of said ring to said groove, said ring adjacent the ejector being provided with an opening, said ejector being substantially U-shaped with one leg extending through said opening and the other leg within said ring, said other leg being formed with a groove for receiving part of said plate for assisting in holding the plate in the vanity case and with a flange underlying 70 part of the plate whereby when the ejector is pulled in a direction away from the bottom of the vanity case said plate will be ejected.

7. In a vanity case provided with a compact plate and a holding ring, of an ejector slidably mounted in said ring, said ejector being movable back and forth in a line substantially parallel to the axis of the plate said ejector having a projection positioned 80 to engage the under side of said plate and remove the plate when the ejector is slid to one of its extreme positions.

WILLIAM G. KENDALL.
